UNITED STATES PATENT OFFICE.

GEORGE McCORD, OF NEW YORK, N. Y.

IMPROVEMENT IN SKATES.

Specification forming part of Letters Patent No. 222,927, dated December 23, 1879; application filed April 22, 1879.

To all whom it may concern:

Be it known that I, GEORGE McCORD, of the city, county, and State of New York, have invented certain new and useful Improvements in Skates, of which the following is a specification.

In the accompanying drawings, Figure 1 represents a side elevation of my improved skate, partly in section; Fig. 2, a front view of the same. Fig. 3 is a side view of a parlor-skate with my improvement, and Fig. 4 is a front view of the same.

Similar letters of reference indicate corresponding parts.

The object of this invention is to so improve the common ice and parlor skates that the speed in skating may be considerably increased and the exercise rendered less fatiguing to the muscles of the foot; and the invention consists of an auxiliary sole-plate that is secured to the heel-plate and cushioned by springs to the supporting sole-plate, being furthermore connected thereto at the front end by a guide and stop device.

Referring to the drawings, A represents a common skate, used for skating on ice, or a parlor-skate. The skate A is provided, at suitable distance above the sole-plate B, with an auxiliary sole-plate, C, of spring-steel or other metal, which is permanently secured to the heel-plate B', and supported, by means of steel or other cushioning-springs, D, on the sole-plate. The front clamps or other fastening devices are applied to the auxiliary sole-plate C, instead of to the sustaining sole-plate B, as heretofore.

The front end of the auxiliary sole plate C is connected by a fixed guide and stop device, E, with the sole-plate B, the guide device E being made either in the shape of a pillar with an enlarged or hook-shaped lower end, a, that is guided in a slot, b, of the supporting sole-plate, or of U shape, the legs of the U passing through holes of the sole-plate, while the

lower connecting or bridge piece forms the stop by contact with the sole-plate, as shown in Figs. 3 and 4.

The use of the auxiliary spring-cushioned sole-plate facilitates skating, as it assists the forward propulsion by "giving" at the front part to the weight thrown thereon by the body in its forward motion. The auxiliary sole-plate increases the speed and heightens the enjoyment of the sport, while the cushioning-springs lessen the fatigue to which the muscles of the foot are exposed by the common skate with rigid sole-plate, and render thereby the art of skating more pleasant and enjoyable.

Having thus described my invention, I claim as new and desire to secure by Letters Patent—

1. The combination, with an ice or parlor skate, of an auxiliary sole-plate that is permanently attached to the heel-plate and supported by cushioning-springs on the sole-plate proper, substantially as set forth.

2. The combination of an ice or parlor skate with an auxiliary spring-cushioned sole-plate, and with a guide and stop device, connecting the same at the front end with the supporting sole-plate of the skate, substantially as specified.

3. In skates, the combination of an auxiliary spring-cushioned sole-plate, that is permanently attached to the heel-plate and supported above the rigid sole-plate, with front clamping and fastening devices secured thereto, substantially as described.

In testimony that I claim the foregoing as my invention I have signed my name in presence of two witnesses this 21st day of April, 1879.

GEO. McCORD.
